AUTOMATIC IRONING SHOE RELEASE

John A. Castricone, Peoria, Ill., assignor to
 Altorfer Bros. Company, Peoria, Ill., a corporation of Illinois

Application May 18, 1948, Serial No. 27,720

6 Claims. (Cl. 38—61)

1

This invention relates to ironing machines and particularly to a safety release mechanism for the ironing shoe regardless of whether the machine is power actuated or there has been an interruption in the power supply. The safety release mechanism is actuated by a lap board projecting outwardly from the front of the ironer over the operator's lap and this mechanism provides a needed and advantageous improvement over my Patent No. 2,253,950, issued August 26, 1941. In the conventional ironer construction, it is customary to provide an ironing bed and shoe between which the work is passed during the ironing operation. These elements are subject to numerous variations, but as a rule the ironing bed is of cylindrical or somewhat arcuate shape and is provided with a fabric surface and suitable padding in a manner well understood in the art. In power driven machines this bed is usually caused to revolve or oscillate in relationship to a heated ironing shoe shaped to conform with the surface of the ironing bed and movable into and out of engagement therewith. It is customary to employ power driven means for causing the ironing bed and shoe to engage and disengage, and ordinarily this power engaging means is synchronized with the roll driving means in such a manner that as the ironer bed begins to move, the bed and shoe are caused to engage, while as the bed ceases its movement, the bed and shoe disengage.

It is also quite customary to provide such mechanisms with an emergency release control and spring retracting means, whereby the ironing elements may be instantaneously disengaged irrespective of the power driving mechanism. The necessity for such an emergency release mechanism will be readily appreciated when it is considered that these ironers are usually supplied with power through the ordinary household cord and plug which may be easily damaged or disengaged in such a manner as to cause a power failure.

It should be pointed out that since the power driving means is utilized both to engage and disengage the ironing elements, any power failure while the ironing elements are in engagement will leave the highly heated ironing shoe in engagement with the work and also in engagement with the fabric surface of the ironing bed, and that if this condition is allowed to continue for more than a very few seconds, the heat of the shoe will scorch or burn both the work being ironed and the fabric surface of the bed.

It is, therefore, a primary object of this inven-

2

tion to provide an ironing machine with an emergency release mechanism that is associated and controlled by a lap board which is an easy and natural control position for the operator and which signals by its position on the ironing machine its natural functions so that the ironing elements may be re-engaged in normal operating relationship after release.

Another important object of the invention is to provide a power driven ironing machine with a manual release mechanism of such design and construction that operation of the manual release will be effective to disengage and separate the cooperating ironing elements irrespective of the operation of the power driving means associated therewith but in which normal operation of such power driving mechanism subsequent to the manual release will be effective to re-engage the ironing elements in normal operative relationship.

Another object of the invention is to provide a power driven ironer with an emergency release effective to separate the ironing elements beyond their normal released position in order to provide a greater safety factor particularly when a hand or arm is drawn between the shoe and roll.

Another object of the invention is to provide an automatic ironer release mechanism which is readily accessible, simple in construction, rugged in operation and economical in manufacture. Release can be accomplished by the operator raising the knees or by raising the body so that the legs will lift the lap board. If any large pieces of clothing would get caught on the edge of the lap board while ironing, the pull caused by the clothes going through the roll would lift the lap board and cause the release thereof.

Referring now to the drawings:

Fig. 1 is a front elevation of an ironing machine constructed in accordance with the principles of this invention;

Fig. 2 is an end elevation of the machine illustrated in Fig. 1;

Fig. 3 is an enlarged fragmental end elevation of the ironing elements and power driving mechanism with certain parts being broken away to more clearly illustrate the ironing element pressure means;

Fig. 4 is a transverse detailed sectional view taken substantially on the plane of the line 4—4 in Fig. 1;

Fig. 5 is a rear elevation of the ironer driving means, certain parts thereof being shown in section;

Fig. 5A is a broken top plan view of my new

release mechanism showing the mechanism as it would appear with the lap board in vertical or non-operative position;

Fig. 5B is an elevational cross sectional view of my new release mechanism associated with the lap board of the ironing machine and showing details of construction as it would appear in vertical or nonoperative position shown in Fig. 5A;

Fig. 5C is a broken elevational view of my new release mechanism shown in Fig. 5B with the lap board in upper operating position ready to release the mechanism and with the lap board in dotted outline to show its release position;

Figs. 5D and 5E are broken elevational views of similar optional forms of release mechanisms later to be explained;

Fig. 6 is a detailed sectional view of the ironer release mechanism, the parts thereof being shown in an emergency released position;

Fig. 7 is a detailed sectional view similar to Fig. 6, the parts being shown in their normal released position; and

Fig. 8 is a detailed sectional view similar to Fig. 7, the parts being shown in their normal operating position.

The ironing bed 11 is here illustrated in the form of a cylinder or roll, mounted for rotation on a bracket 12 which may be cast integrally with a gear housing 13 and supported in any desirable manner upon the ironer frame 15. A driving motor 16 is bolted on the gear housing 13 and serves to rotate or oscillate the ironing bed 11 through the medium of a suitable gearing (not shown) housed within the housing 13.

The motor operation of the ironer is controlled by control lever 17 pivotally mounted on the pin 18 and connected with the control shaft 19 journalled in the wall of the gear housing 13 by means of a control rod 21. The arrangement is such that the motor 16 will run continuously while the ironer roll or bed 11 may be engaged or disengaged from driving connection by the actuation of the control lever 17. When the control lever 17 is momentarily depressed, the roll 11 will be engaged and driven by means of the motor 16 until such time as the lever 17 is again depressed in order to disengage the driving connection and stop the roll.

The ironer shoe 31 is pivotally mounted on a pin 32 carried at the upper end of a movable arm 33 pivoted to the standard 34 by means of a pin 35. The shoe 31 includes a concave arcuate ironing surface 36 which is adapted to bear against the similarly shaped surface of the ironing bed 11.

Power actuated pressure engagement between the shoe 31 and the bed 11 is accomplished by mounting an eccentric 41 (Fig. 3) on a fixed shaft 42 within the gear case 13 and by operatively connecting the eccentric strap 43 with the movable ironing shoe 31 in such a manner that the shoe 31 will move into and out of engagement with the bed or roll 11 in accordance with the position of the rotating eccentric 41. The arrangement is such that whenever the control lever 17 is momentarily depressed and the ironing bed 11 begins to rotate, the eccentric 41 will revolve 180° from the position shown and will move the eccentric strap to the right from the position shown in Fig. 3, thereby causing the movable arm 33 to pivot downwardly about the pin 35 in such a manner as to bring the arcuate surface 36 of the ironing shoe 31 into pressure engagement with the ironing bed 11. When the

eccentric 41 has rotated 180° and brought the ironing elements into engagement, an automatic clutch (not shown) disengages the driving connection to the eccentric 41 and the parts remain in engaged position until the operating lever 17 is again actuated. When this is done the driving connection to the ironing bed 11 is disengaged and simultaneously the eccentric 41 is again engaged and rotates 180° back to the normal disengaged position as illustrated in Fig. 3. This will, of course, result in moving the eccentric strap 43 back to the left and in allowing this motion to be transmitted to the swinging arm 33 in such a manner as to disengage the shoe 31 from the ironing bed 11 and return the shoe 31 to the normal released position illustrated.

The eccentric strap 43 is provided with a slot 44 in order to engage a pin 45 carried by a crank arm 46 fixedly mounted on an oscillating pressure shaft 47 journalled in a bearing 48 (Fig. 5) formed integrally with the walls of the gear housing 13. A coiled compression spring 49 is carried within a suitable socket in the eccentric strap 43 in order that a certain amount of yielding will be permitted between the ironing elements when they are in engaged position.

Predetermined pressure adjustment between the roll 11 and shoe 31 is accomplished by an arm 51 (Figs. 5-8) which is secured to the oscillating pressure shaft 47 by means of a cross pin 52 and which carries an adjustable index plate 53 angularly movable with respect to the arm 51 within the limits prescribed by the adjusting slot 54. This index plate may be clamped in any predetermined angular setting with respect to the arm 51 by means of a cap screw 55. The driving shaft 47 extends beyond the index plate 53 in order to provide a pilot portion 56 freely rotatable within the drilled opening 57 of a driven clutch element 58. A driven oscillating pressure shaft 59 is secured within the drilled opening 57 in axial alignment with the driving pressure shaft 47 but is rigidly connected with the clutch element 58 by a cross pin 61. A spring pressed plunger 62 is slidably mounted in a slide-way 63 in the clutch element 58 and is normally held in locked engagement within a suitable orifice 64 in the index plate 53 by means of a compression spring 65 bearing against a threaded plug 66.

Examination of Figs. 5 and 6 will show that the arrangement is such that the oscillating movement of the pressure shaft 47, as imposed by means of the eccentric 41 and eccentric strap 43, will be transmitted through the pin 52 and arm 51 to the index plate 53 and then through the plunger 62 and driven clutch element 58 in such a manner as to oscillate the driven pressure shaft 59 in accordance with the movement of the driving pressure shaft 47 whenever the plunger 62 is seated within the orifice 64. The degree of pressure to be exerted between the ironing elements is adjustable in accordance with the requirements of the work by adjusting the position of the index plate 53 with respect to the arm 51 by means of the screw 55.

The opposite end of the driven pressure shaft 59 is journalled in a bearing 71 carried by the angle plate 72 secured on the lower surface of the top plate 73 of the base 15 by any desirable means, and is provided with a crank arm 74 (see Fig. 4) rigidly mounted at the extreme end by means of the cross pin 75.

The movement of the driven oscillating pressure shaft 59 is transmitted to the ironer shoe 31

by means of a connecting rod 76 mounted on the crank pin 77 carried by the crank 74 and extending upwardly to the pin 78 secured in bosses 79 within the walls of the swinging arm 33. The shoe 31 is normally urged out of engagement with the roll 11 by a coiled tension spring 81 which extends downwardly from the pivot pin 35 to a hole 83h in carrier 83 (see Fig. 5). The cap screw 82 serves to secure the carrier or adjustable limit stop member 83 which is slideable along the connecting rod 76 and which may be clamped in any position therealong as limited by the adjusting slot 84 for adjusting the tension of spring 81.

Examination of the drawings will clearly indicate that the position of the handle 87 behind the shoe 31 introduces a burning hazard to the operator because the hand and arm must be extended over the hot shoe to actuate the handle. It will be obvious that the limit stop 83 may be adjusted for contact with a fixed limit corresponding to the shaft 86 and thereby the handle 87 may be eliminated, thus eliminating the hazard described above and providing an optimum clearance between the shoe and roll. Although in the following description I retain the handle 87, it will be understood and appreciated that I may substitute the adjustment mechanism with a fixed stop 86.

The lap board 191 (see Figs. 1, 5B and 5C) is a new idea to my ironing machine. It provides a hinged tray or shelf to keep damp garments out of the operator's lap and has proved to be a desirable addition to the ironing machine. The lap board extending across the operator's lap is in ready convenient position to the operator and it is pivotally mounted in a conventional manner as clearly shown in Figs. 1 and 2. My use of the lap board 191 as a release lever is new and inasmuch as it extends over the operator's lap it is in obvious position to perform its functions as a releasing lever as will now be explained. The lap board 191, when in vertical stored position as shown in Fig. 5B, has no control over the release mechanism because the link 192 with its slotted connection 193 with link 194 has no operative connection with the release plunger as will be clearly understood by an examination of the drawings. The lap board is held at any position of its travel by friction between hinge pin 191p and spring clip 191c. This friction is adjustable by screw 191s.

However, when the lap board 191 is moved to horizontal operating position as shown in Fig. 5C, the slot 193 is moved to operative engagement by reason of the lever connections now established between the lap board 191, the lost motion lap board connector member 191a, the link pin connection 192p and the slot 193 in the link 192 with the link 194.

When an emergency release is necessary or expedient, this may be quickly and conveniently effected by the operator merely raising the lap board 191 to the dotted line position as shown in Fig. 5C. When the lap board 191 is so pivoted upwardly as shown in dotted outline, the bell crank 195 pivotally attached to the link 194 and the link 196 (see Fig. 5A) moves the spring pressed plunger 62 out of the clutch orifice 64, whereupon the ironer shoe 31 is released and removed from the roll 11.

Although in the foregoing I have discussed a manual emergency release by actuation of the lap board by the operator which may be accomplished in a wide variety of ways—even without use of the hands—it will be appreciated that the

same results can be accomplished by clothes moving over the lap board. For instance, when clothes are moving over the lap board they may not be properly fed into the roll by the operator 5 whereupon the pull of the clothes on the lap board and particularly catching of clothes thereon may effectively release the mechanism and thus automatically release the roll. This is an important feature because at times the operator 10 may be too engaged to properly feed the clothes between the roll and shoe.

Many variations of the lap board structure 15 may be made without departing from the spirit of the invention. For example, a control rod 197 lying around the lap board and connected to the release parts 191a, 192 and 192p, as clearly shown in Fig. 5D, may be utilized to perform the release functions of the lap board 191. Thus, by raising the control rod as shown in dotted outline in Fig. 5D, the same emergency release of the shoe 31 may be effected.

Further by eliminating the lap board 191 and using merely a simple push release rod 198 connected to a revised push release bell crank 195, 20 the structure may assume a simple push release actuated by the push rod 198 as shown in Fig. 5E.

I desire to teach and claim an emergency release utilizing an actuating lever extending outwardly over the front lap section of the ironer 25 which may be actuated by horizontal or angular pushing movement that may be effected by the operator either with or without the use of the hands or automatically by the goods being ironed.

35 Reset of the emergency release may be readily accomplished by returning the lap tray 191 to its normal horizontal position as clearly shown in Fig. 5C. Here an important benefit is attained because the lap board 191 in its angularly upward position clearly signals the operator that the release mechanism has been actuated. The operator would thus naturally move the lap board 191 to its normal horizontal position and thus the emergency release is ready for reset. The above natural movements of the lap board 40 45 191 have proved of considerable advantage because sometimes the operator fails to reset the mechanism when the release control lever is placed in a less conspicuous and obvious position.

In many cases the safety release is placed above 50 the shoe, but when the shoe is in released position, the release handle is behind the shoe so that the operator's hand must pass over the hot shoe, grasp the handle and pull forward, running the risk of having her wrist burned as she 55 exerts pulling power on the handle.

As hereinbefore pointed out, the control mechanism is such that the power drive is utilized not only to move the shoe 31 into engagement with the roll 11, but also to move these ironing 60 elements out of engagement, and, therefore, the emergency release lap board 191 is provided in order that the ironing elements may be instantly disengaged irrespective of the power drive, or in the event of a power failure. Moving the lap board 191 upwardly will withdraw the plunger 62 from the orifice 64 in the index plate 53 against the action of the compression spring 65. This movement completely disengages the operating connection between the driving pressure shaft 47 and the driven pressure shaft 59, leaving the shaft 59 free to move under the influence of the tension spring 81 which will act to draw the connecting rod 76 upwardly, thus pivoting the swinging arm 33 about the pin 35 and withdrawing

the shoe 31 from engagement with the ironing bed 11.

In the normal operation of the machine the operator will first place the work to be ironed in position on the ironer roll 11 and will then actuate the knee control 17 to start the rotary movement of the roll 11 and to cause the ironing shoe 31 to move into pressure engagement with the work positioned on the roll 11. This is accomplished by means of the control rod 21 which extends between the knee control lever 17 and the control shaft 19 journaled in the wall of the gear housing 13. The movement of the control shaft 19 will actuate suitable clutch mechanisms housed within the gear box 13 to rotate the eccentric 41 through 180° of movement from the position shown in the drawings and thus move the eccentric strap 43 to the right, as viewed in Fig. 3, in such a manner as to oscillate the driving oscillating shaft 47 and draw the swinging arm 33 downwardly by means of the connecting rod 18 and crank 14 to force the ironing shoe 31 into pressure engagement with the roll 11.

The ironing shoe 31 will remain in pressure engagement with the rotating roll 11 until the knee control 17 is again actuated, at which time an automatic clutch mechanism housed within the gear box 13 will again rotate the eccentric 41 through 180° of movement to return the parts to the position shown in Fig. 3 to disengage the shoe 31 from the roll 11 and stop the rotary movement of the roll 11. The details of the mechanism within the gear box 13 by which this action is accomplished, have not been described in the present application since it forms no essential part of the invention and since it has been fully described in the United States Patent No. 2,115,941, issued to this applicant on May 3, 1938.

In view of the complete description of this mechanism set out in the specification of said patent, detailed description in this application is not considered necessary, but it should be pointed out that the mechanism provides a power operated means to release these elements from engagement and move them into spaced relationship with each other. Both of these functions are accomplished by power transmitted through the gear box 13 from the motor 16, and the knee control lever 17, control rod 21, and control shaft 19 merely serve as manual actuating means whereby the power operated mechanism may be caused to operate according to the will of the operator.

While I have shown and described a preferred embodiment of this invention as required by the patent statutes, I am aware that it is subject to numerous modifications without departing from the invention spirit and I, therefore, do not wish to be limited except as by the scope of the appended claims.

I claim:

1. In a pressing machine, an ironing member, a pressing shoe cooperating with said member, means for controlling said shoe comprising a pair of aligned shafts the drive one of which is connected with the shoe to move said shoe in one direction, a clutch having a slidable clutch pin connecting said shafts together, a lap board mounted upon said machine for upward and downward swinging movements, a link pivoted to said lap board and having a slot in its free end portion, a second link having a slidable pin connection with said slot, a bell crank lever pivoted to the machine and having one arm thereof connected to said second link and a third link connecting the other arm of said bell crank lever

with said clutch pin whereby upward movement of said lap board will withdraw said pin and disconnect said clutch, said slot allowing said lap board to be swung downwardly.

2. In a pressing machine, an ironing member, a pressing shoe cooperating with said member, means for controlling said shoe including a pair of aligned shafts, clutch members upon the adjacent ends of said shafts, a spring pressed slidable pin connecting said clutch members together, means connecting said shoe with one shaft, means for operating the other shaft, a lap board mounted upon said machine, a bell crank lever pivoted on the machine and having one arm connected to said slidable pin and a lost motion link connection between the other arm of said bell crank and the lap board.

3. In a pressing machine, an ironing member, a pressing shoe cooperating with said member, means for controlling said shoe comprising a pair of aligned shafts the drive one of which is connected with the shoe to move said shoe in one direction, clutch blocks upon the adjacent ends of said shafts, a slidable spring pressed pin connecting said clutch blocks together, a lap board mounted upon said machine for upward tilting movement, a connection between said lap board and said spring pressed pin arranged to withdraw said pin and disconnect said clutch by upward movement of said lap board.

4. In a pressing machine, an ironing member, a pressing shoe cooperating with said member, means for controlling said shoe comprising a shoe operating mechanism connected therewith and having a clutch, means for disconnecting said clutch and releasing said shoe comprising a lap board mounted upon said machine and a connection between said lap board and clutch to disconnect said clutch and release said shoe by upward movement of said lap board, said connection between said lap board and clutch having a lost motion connection whereby said lap board may be swung downwardly into a vertical plane.

5. In a pressing machine, an ironing member, a pressing shoe cooperating with said member, means for controlling said shoe comprising a shoe operating mechanism connected therewith and having a clutch, kinematic means for disconnecting said clutch and releasing said shoe, said means comprising a lapboard mounted upon said machine and including a lost motion device connected between said lapboard and said clutch to disconnect said clutch and release said shoe by upward movement of said lap board.

6. In a pressing machine, an ironing member, a pressing shoe cooperating with said member, means for controlling said shoe comprising a shoe operating mechanism connected therewith and having a clutch, means for disconnecting said clutch and releasing said shoe, said means including a lap board mounted upon said machine and adapted for swinging movement about a substantially horizontal axis, a lost motion device and a bell crank lever connected between said lap board and said clutch for disconnecting said clutch upon upward swinging movement of said lap board.

JOHN A. CASTRICONE.
